(57) **CLAIM**

The ornamental design for a four-legged human transporter, as shown and described.

DESCRIPTION

FIG. 1 is a front right side perspective view of a four-legged human transporter according to our design;

FIG. 2 is a right side elevation view thereof, the left side being a mirror image thereof;

FIG. 3 is a top plan view thereof;

FIG. 4 is a front elevation view thereof;

FIG. 5 is a rear elevation view thereof; and,

FIG. 6 is a bottom plan view thereof.

Where included, the broken lines showing environment or structure are for illustrative purposes only and form no part of claimed design.
